REFRIGERATOR ASSEMBLY

Guyon L. C. Earle, Forest Hills, N. Y., assignor,
by mesne assignments, to Earle Kitchen Unit
Corporation, New York, N. Y., a corporation of
New York

Application August 11, 1945, Serial No. 610,317

5 Claims. (Cl. 62—89)

1

This invention relates primarily to refrigerators and more specifically, although not necessarily, to refrigerators of the type having a sealed operating unit and to their assembly.

Many refrigerators being manufactured today are of the type which employs a sealed operating unit. Such a unit usually comprises an evaporator and cold control element, a compressor-condenser element, and various tubes and electrical connections between these two elements or between one or both of them and a source of power. In order to save time in setting up the refrigerator in the user's kitchen and also because of the use of insufficiently skilled personnel for this purpose, the refrigerant is placed in the operating unit at the factory and all the connections between the two elements are sealed. It has been found difficult to assemble such a sealed refrigerator operating unit in refrigerators of the two-part type such as, for example, the set-back refrigerator disclosed in Patent 2,312,326 issued March 2, 1943, to Guyon L. C. Earle. The present invention, in an important aspect thereof, relates to means for assembling two-part refrigerators of the type employing sealed operating units and the construction of such refrigerators but other aspects of the invention will be readily apparent from the description below.

It is an object of this invention to provide improved means for assembling refrigerators having upper and lower portions and employing an operating unit of a refrigerator a portion of which is located inside the refrigerator and the rest outside it.

It is another object of this invention to provide means for temporarily supporting the evaporator of a refrigerator from the lower portion of a two-part refrigerator before the upper portion thereof is attached thereto.

It is another object of this invention to provide improved and readily accessible means for holding together the upper and lower portions of a two-part refrigerator.

It is still another object of this invention to provide a novel combined gasket and channel or guide member for tubes and connections such as, for example, of the operating unit of a refrigerator.

It is a further object of this invention to provide a novel combined gasket and channel or guide member for the tubes and connections used with the various elements of a refrigerator sealed operating unit which can be attached to the evaporator-cold control element of the op-

erating unit before the refrigerator is finally assembled.

In accordance with a specific embodiment of the present invention, described by way of example for purposes of illustration, there is provided a novel refrigerator of the "set-back" type, that is, one having an upper insulated refrigerated portion and a lower insulated refrigerated portion, the front plane of the upper portion being set back from the front plane of the lower portion, and a table-top member placed in front of the upper portion and on top of the lower portion. This refrigerator employs a refrigerator operating unit of the sealed type, the evaporator and cold control element or unit being placed in the upper portion of the refrigerator and the compressor-condenser element or unit being placed outside the refrigerator preferably at the side of the lower portion thereof. At the upper part of the lower portion across the opening at the top thereof are placed two supporting members in accordance with the invention to hold the evaporator-cold control unit in position before the upper portion of the refrigerator is fastened in place. Means are also provided for fastening the evaporator to the upper portion after the latter has been placed in position over the opening in the top of the lower portion of the refrigerator. Various pairs of bracket members, at least one pair on each side, are provided for squeezing the gasketing between the two portions of the refrigerator and thus preventing air from getting into the interior thereof. One of each pair is fastened to the upper portion and the other one of each pair is joined to the lower portion. Bolts with wing nuts therefor are used to squeeze the bracket members of each pair together. The gasketing material between the two portions includes or surrounds a novel protecting member in accordance with the invention which is a combined channel or guide member and gasket for the various tubes and connections between the portion of the operating unit located inside the two-part refrigerator and the portion located outside it and to a source of power. Other novel features of the refrigerator in accordance with this invention will be apparent from the description below and from the claims appended thereto.

The invention will be more readily understood by referring to the following description taken in connection with the accompanying drawing forming a part thereof, in which:

Fig. 1 is a perspective view of the lower por-

tion of a two-part "set-back" refrigerator and of a cabinet adjacent thereto, the evaporator unit of the refrigerator being shown in the position it occupies during transportation of the refrigerator prior to final assembly thereof;

Fig. 2 is a perspective view of the apparatus of Fig. 1 with the evaporator unit and the protecting member being shown in the positions they respectively occupy during one step of the assembly operation;

Fig. 3 is a perspective view of a protecting member in accordance with this invention;

Fig. 4 is a partially exploded perspective view of the member shown in Fig. 3;

Fig. 5 is a perspective view of the lower portion 15 of the right hand member in Fig. 4;

Fig. 6 illustrates one manner in which the protecting member can be attached to the evaporator;

Fig. 7 is a perspective view of the lower portion 20 of the refrigerator of Fig. 1 showing means for temporarily supporting the evaporator during the assembly process and the lower ones of two pairs of brackets for holding together the upper and lower portions of the refrigerator;

Fig. 8 is a perspective view, with portions broken away, of the upper portion of the refrigerator and of a part of the lower portion thereof after these two portions are joined together; and

Fig. 9 is a fragmentary front elevation view of the refrigerator with portions broken away to show a part of the interior thereof.

Referring more particularly to the drawings, Figs. 1 and 2 show, by way of example for illustrative purposes, the lower portion 10 of a refrigerator 9 of the "set-back" type and of a cabinet adjacent thereto. The upper portion 40 of the refrigerator 9 is shown in Figs. 8 and 9. Reference is made to the following patents of Guyon L. C. Earle which show both upper and lower portions of refrigerators of the "set-back" type: 2,180,460 issued March 14, 1939, 2,312,326 issued March 2, 1943, and 2,328,130 issued August 31, 1943. The lower portion 10 contains a plurality of drawers 11, 12, 13 and 14 for storing food or other articles to be refrigerated. The upper portion 40 includes the evaporator 19, ice cube trays 50 and shelves 51. Doors 52 and 53 serve as closure members. Above the lower portion of the refrigerator and in front of the upper portion 40 thereof a table-top member 15 is provided while at the side of the refrigerator is a cabinet member 46 within which is supported the compressor-condenser element 17 of a sealed refrigerator operating unit 18. The unit 18 also includes the evaporator-cold control element 19 and various connections and tubes 20 between the inside of the refrigerator and the outside thereof. In Fig. 1, the element 19 has been shown in the position it occupies during transportation, it being fastened to a rack or by other means at the rear of the cabinet section 46, and in Fig. 2 it has been shown in the position it occupies during the step in the assembly process just before the upper portion 40 of the refrigerator is fastened to the lower portion 10. During this step it rests on two supporting members 41 and 42 connected, for example, between the back of the lower portion 10 and the underside of the top covering thereof across the opening 34 in the top of the lower portion 10. Of course, other forms of supporting members or supporting members of this type positioned in different locations can be used, if desired.

Surrounding the tubes and connections 20,

which for example, include (see Fig. 6) an electrical connection 21 to the cold control 24, a capillary tube 22 to the high side of the evaporator and a large tube 23 to the low side thereof, is a gasketing or protecting member 25 in accordance with one aspect of this invention. This protecting member comprises upper and lower members 26 and 27 which may be resilient or non-resilient and a resilient collar member 28 sheathing one end of each of the members 26 and 27. If desired the member 28 can be non-resilient. The lower member 27, as shown in Fig. 5, has grooves 29 in the upper and right hand surfaces thereof of the proper size to provide channels for the lower half of each of the tubes or connections 20 while the inside surfaces of the L-shaped member 26 is correspondingly grooved to provide, as shown in Fig. 6, channels for the upper half of each of the tubes and connections 20. A plate 30 is attached to the members 26 and 27 and helps to hold these two members together. Holes through which the connections or tubes 20 pass are provided in the plate 30. The resilient cap or collar 28 can be made in one piece, of soft rubber or similar material, with a slit 31 therein which can be vulcanized or otherwise sealed after the collar is slipped over the members 26 and 27 which may be bolted together. The plate 30 can be dispensed with, if desired. It can be made of two parts if it is desired to fasten it to the protecting member after the tubes and connections 20 have been fastened to the elements of the operating unit 18. The collar 28 can be made without the slit 31 and slipped over the members 26 and 27 if the tubes or connections 20 have not yet been fastened to the elements of the unit 18.

In assembling the refrigerator, the evaporator 19 is lifted to the position shown in Fig. 2 where it rests on the members 41 and 42 and where the collar 28 fits into a prefabricated groove or slot 32 (see Fig. 1) in the vertical wall 33 of the lower portion of the refrigerator. If desired the groove or slot 32 can be in the upper portion of the refrigerator instead of the lower portion or it can be made of two grooves each half as deep and a portion thereof cut in each of the two portions of the refrigerator. The groove 32, in any event, is just the size for a snug fit of the collar 28 which prevents any cold from getting out of the refrigerator. If they are not already in place, the lower bracket member 43 (on the left side) and the members 44 (on the right side), the latter in front of and behind the groove 32, respectively, are fastened to the lower portion 10. The member 43 is inside the member 10 (where it will not show) and the members 44 are outside the refrigerator (where they can be easily reached but will also not show because they are in the cabinet member 46). Then the upper portion 40 of the refrigerator is placed over the top opening 34 of the lower portion 10 of the refrigerator with proper gasketing 46 between the two portions. The evaporator 19 is fastened to the inside of the upper portion 40 by means of screws passing through holes 47 into the walls of the upper portion. If desired it may still rest on the members 41 and 42 if the position of the holes 47 is properly chosen. The upper bracket members 48 and 49 are tightly connected to the corresponding members 43 and 44 by turning the wing nuts 45, thus tightly squeezing the gasketing 46 and the protecting member 25, holding it tightly within the groove 32 and ensuring an air-and-moisture tight insulated enclosure. The bracket members are

easily accessible if it is desired to later disassemble the refrigerator. Moreover, the evaporator can be easily removed by unscrewing the bolts after the racks and ice cube trays 50 have been taken out.

Various obvious changes other than those specifically mentioned will occur to those skilled in the art and it is intended that all such changes which fall within the scope of the appended claims be covered thereby.

What is claimed is:

1. A mechanical refrigerator comprising a lower insulated portion and an upper insulated portion having a smaller dimension from front to rear than said lower portion, resilient gasketing between the members, and bolting means, one inside and one outside the refrigerator, for fastening the upper portion to the lower portion and for tightly squeezing said gasketing to ensure an air-and-moisture tight joint, said gasketing including a protecting member for tubes passing into said refrigerator from the outside thereof.

2. A mechanical refrigerator comprising upper and lower insulated portions each having vertical walls, said upper portion including a vertical wall which is substantially in the same plane as one of the vertical walls of said lower portion, one of said vertical walls having a groove therethrough at the edge thereof adjacent said vertical wall of said other portion, a refrigerator operating mechanism including an evaporator unit, a compressor-condenser unit and connections between the units, means for mounting said evaporator unit inside said refrigerator and said compressor-condenser unit on the outside thereof in such position that said connections pass through said groove, and a protecting member encircling said connections as they pass through said groove, said protecting member comprising two non-resilient members having grooves therein in the surfaces touching each other so as to form air-tight conduits for said connections.

3. A mechanical refrigerator comprising upper and lower insulated portions each having vertical walls, said upper portions including a vertical wall which is substantially in the same plane as one of the vertical walls of said lower portion, one of said vertical walls having a groove therethrough at the edge thereof adjacent said vertical wall of said other portion, a refrigerator operating mechanism including an evaporator unit, a compressor-condenser unit and fluid connections between the units, means for mounting said evaporator unit inside said refrigerator and said compressor-condenser unit on the outside thereof in such position that said connections pass through said groove, and a protecting member encircling said connections as they pass through said groove, said protecting member comprising two members having grooves therein in the surfaces touching each other so as to form conduits for said connections, and an element of resilient material surrounding the end of each of said two members nearer the evaporator and in contact with said groove in the wall, said two members 65

being shaped so that one nests within the other and so that the conduits are bent.

4. A mechanical refrigerator comprising upper and lower insulated portions each having vertical walls, said upper portion including a vertical wall which is substantially in the same plane as one of the vertical walls of said lower portion, one of said vertical walls having a groove therethrough at the edge thereof adjacent said vertical wall of said other portion, a refrigerator operating mechanism including an evaporator unit, a compressor-condenser unit and fluid connections between the units, means for mounting said evaporator unit inside said refrigerator and said compressor-condenser unit on the outside thereof in such position that said connections pass through said groove, and a protecting member encircling said connections as they pass through said groove, said protecting member comprising two members having grooves therein in the surfaces touching each other so as to form conduits for said connections, and means for securing said protection member to said evaporator.

5. A mechanical refrigerator comprising upper and lower insulated portions each having vertical walls, said upper portion including a vertical wall which is substantially in the same plane as one of the vertical walls of said lower portion, one of said vertical walls having a groove therethrough at the edge thereof adjacent said vertical wall of said other portion, a refrigerator operating mechanism including an evaporator unit, a compressor-condenser unit and fluid connections between the units, means for mounting said evaporator unit inside said refrigerator and said compressor-condenser unit on the outside thereof in such position that said connections pass through said groove, and a gasket member encircling said connections as they pass through said groove, said gasket member comprising two members having grooves therein in the surfaces touching each other as to form conduits for said connections, means for securing said protection member to said evaporator, and bracket means for fastening the upper portion and the lower portion of the refrigerator together in such a way that the gasket member is squeezed to make a tight fit.
